CULINARY BEATER

James L. Hvale, Chicago, Ill., assignor to Ekco Products Company, Chicago, Ill., a corporation of Delaware

Filed Aug. 23, 1960, Ser. No. 61,862

Term of patent 14 years

(Cl. D44—1)

FIG. 1 is a side elevation of a culinary beater showing my new design.

FIG. 2 is a fragmentary side elevation of the article as it appears from the side reverse to that shown in FIG. 1.

FIG. 3 is a top plan view thereof.

FIG. 4 is a fragmentary end elevation showing the article as the same appears when viewed from the left hand side of the article as shown in FIG. 1.

The essential features of my design reside in the portion shown in solid lines on the drawing.

I claim:

The ornamental design for a culinary beater, and described as shown.
